[57] CLAIM

The ornamental design for a housing for an electrical connector, as shown.

DESCRIPTION

FIG. 1 is a top, front and right side perspective view of a housing for an electrical connector showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and

FIG. 8 is a rear, bottom and left side perspective view thereof.

*FIG. 1**FIG. 2**FIG. 3**FIG. 4*

FIG. 5

FIG. 6

FIG. 7

FIG. 8
